United States Patent Office

Des. 227,660
Patented July 10, 1973

227,660

SHOPPING BAG HANDLE HOLDER

Kane Y. Konno, 32-76 32d St.,
Astoria, N.Y. 11106

Filed Mar. 27, 1972, Ser. No. 238,717

Term of patent 14 years

Int. Cl. D9—99

U.S. Cl. D9—292

Fig. 1.

Fig. 2.

Fig. 3.

Fig. 4.

FIG. 1 is a perspective view of a shopping bag handle holder showing my new design;

FIG. 2 is a side elevational view;

FIG. 3 is an end elevational view; and

FIG. 4 is a top view thereof.

I claim:

The ornamental design for a shopping bag handle holder, as shown and described.
